UNITED STATES PATENT OFFICE.

CHARLES FRANZ, OF NEW YORK, N. Y., ASSIGNOR TO A. A. VANTINE & CO.,
OF SAME PLACE.

DESIGN FOR WOVEN FABRIC.

SPECIFICATION forming part of Design No. 28,622, dated May 10, 1898.

Application filed March 1, 1898. Serial No. 672,206. Term of patent 31 years.

To all whom it may concern:

Be it known that I, CHARLES FRANZ, a subject of His Majesty the Emperor of Germany, residing at Jamaica, borough of Queens, city and State of New York, have invented and produced a new and original Design for a Woven Fabric, of which the following is a specification, reference being had to the accompanying drawing, forming part thereof, in which is represented a plan view of a piece of fabric embodying my design.

One of the leading features of the design consists in a conventional heart-shaped figure A, with a border of a half-leaf, which figure contains a rosette-center B, decorated with an embroidery effect; also buds and leaves. This figure is joined and interlaced with foliated sprays, buds, and half-leaves to

a conventional oval-shaped figure C, which contains a rosette-center D, decorated with flowers, buds, sprays, and embroidery effect. Other features of the design are in a border consisting of a panel E, rosettes with buds and scrolls, and a panel F, consisting of rosettes, buds, and leaves interlaced with a conventional scroll effect decorated with rosettes, buds, and leaves, and embroidery effect, the whole design having an oriental embroidery effect throughout.

I claim—

The design for a woven fabric herein shown and described.

CHARLES FRANZ.
